REVOLVING DOOR SPEED CONTROL

Thurloe M. Hagenbook, Evansville, Ind., assignor,
by mesne assignments, to International Door
Company, Evansville, Ind., a corporation of
Illinois

Original application September 10, 1932, Serial
No. 632,627. Divided and this application Sep-
tember 15, 1933, Serial No. 689,633

15 Claims. (Cl. 188—187)

My invention relates broadly to speed control mechanism and more particularly to the structure of a speed control adapted for installation in connection with revolving doors.

5 This application is a division of my application Serial No. 632,627, filed September 10, 1932, entitled Revolving door speed control.

One of the objects of my invention is to provide a construction of speed control device for 10 attachment to revolving doors of various types for controlling the speed of revolution of the revolving door and increasing the safety of operation.

Another object of my invention is to provide 15 a simplified construction of speed control for revolving doors which may be inexpensively manufactured on a quantity production basis and utilized for precision operation in the control of revolving doors of various makes.

20 Still another object of my invention is to provide a construction of speed control mechanism in which a drum type friction brake is operated by the movement of a centrifugal actuator as the speed of the rotary shaft to which the control mechanism connects is increased.

25 A further object of my invention is to provide a construction of centrifugal governor for revolving doors wherein substantial load is added to the door under conditions where the rate of 30 speed at which the door is operated increases beyond a predetermined value.

35 A still further object of my invention is to provide an attachment capable of engaging the upper pintle of the revolving door and establish a geared connection with a centrifugal governor and friction brake device for controlling the speed of operation of the revolving door within predetermined limits.

Another object of my invention is to provide 40 a construction of centrifugally operated clutch for a governor for revolving doors having means for rendering a friction brake effective when the speed of rotation of the revolving door tends to exceed a predetermined rate.

45 Other and further objects of my invention reside in the construction of friction brake revolving door speed control as set forth more fully in the specification hereinafter following by reference to the accompanying drawings, in which:

50 Figure 1 is a cross-sectional view taken through the revolving door speed control of my invention with some of the parts illustrated in side elevation; Fig. 2 is a side elevational view of the revolving door speed control showing the support-
55 ing rails constituting the trolleys and the socket

bearing for the upper portion of the revolving door illustrated in cross-section and looking in the direction of arrow A of Fig. 1; Fig. 3 is a horizontal sectional view of the revolving door speed control device of my invention taken on line 3—3 of Fig. 1; Fig. 4 is a horizontal sectional view taken through the speed control on line 4—4 of Fig. 1 on an enlarged scale; Fig. 5 is a cross-sectional view taken through the speed control on line 5—5 of Fig. 1; Fig. 6 is a cross-sectional view taken through the speed control on line 6—6 of Fig. 1; Fig. 7 is a side elevation of the ratchet mechanism employed in connection with the centrifugal governor mechanism in the revolving door speed control device of my invention; and Fig. 8 is a schematic view showing the manner in which the revolving door is assembled for connection with the speed control device.

Referring particularly to the drawings, reference character 1 designates the wings of the revolving doors arranged to revolve around the central axis 2 immediately below the rails 3 constituting the trolley support for the revolving doors. The wings 1 of the revolving doors are suspended from the rails 3 by means of roller members 4 journaled on the ends of shaft 5 connected through support 6 with member 7 which engages the upper rail 8 of the revolving doors. The upper rail 8 is provided with socket member 9 within which annular member 10 is seated for housing the annular members 11 and 12 having ball races for guiding ball bearings 14 therebetween. The annular member 10 has upwardly projecting cylindrical walls 10a and 10b between which, the annular members 11 and 12 are confined and into which the annular member 16 projects and rests upon the upper portion of the annular ring member 12. The member 16 is screw threaded at 16a to receive the screw threaded end of the tubular member 2, as shown. The upper portion of member 16 is provided with a socket 16b into which there extends the cylindrical liner 17. The cylindrical liner 17 provides a socket which is adapted to receive the spring pressed pin 18. The spring pressed pin 18 is chamfered at 18a to permit ready insertion or removal of pin 18 from the socket formed interiorly of the liner 17. The pin 18 is mounted within a cylindrical guide 19 which projects from the lower plate 20 forming part of the housing of the speed control device. The cylindrical guide 19 has a screw device 21 extending through one side thereof with a pin 22 from the end of the screw device projecting into a socket 23 in one side of the projectible pin 18 so that pin 18 is free to move vertically against 55

the resistance offered by coil spring 30. It will be observed that the upper portion of annular member 16 has a beveled surface represented at 16c which enables the revolving door assembly to be interconnected with the speed control governor mechanism by rolling the revolving doors on the trolleys to a position where the beveled surface contacts with the chamfered edge 18a of pin 18, thereby raising pin 18 and allowing the pin to drop into the socket formed by the liner 17. The revolving door structure is thus centered with respect to the governor mechanism, and the gear teeth 16d on the periphery of the annular member 16 are brought into mesh with the gear teeth on gear 32. Gear 32 is carried by stub shaft 33 which is journaled in ball bearings 34 and 35. Ball bearings 34 are mounted in races supported in plate 20. Ball bearings 35 are mounted in races supported in casting 36 which extends in a position substantially chordal to the casing within which the speed control mechanism is housed. The casting 36 which is illustrated more clearly in Figs. 2 and 5, is secured to plate 20 by means of screws 36a and is provided with downwardly depending lugs 37 through which set screws 38 pass and engage rails 3 forming part of the stationary equipment of the revolving door. In order to further mount the governor rigidly with respect to the stationary frame structure beneath which the revolving door moves, I provide the casting 39 beneath the governor housing and substantially chordal to the governor housing and connected thereto through screw members 39a. The casting 39 has depending lugs 40 through which the securing screws 41 pass, which screws grip rails 3 as represented in Fig. 6 thereby insuring a rigid mounting for the governor housing immediately above the rails 3.

The transversely extending plate 20 has the cover member 31 secured thereto by means of bolt members 42. The cover member 31 and plate member 20 are recessed as indicated at 31a and 20a to receive roller bearing guide rings represented at 43 and 44 respectively. A stub shaft 45 is journaled vertically through casing 31 and plate 20 by means of annular members 46 and 47 aligned with respect to the annular members 43 and 44 by means of conical shaped roller bearings 48 and 49, as shown. Shaft 45 is provided with gear teeth 50 on the lower projecting end thereof adapted to mesh with gear 51 carried by stub shaft 33. It will be seen that rotation of the revolving doors 1 serves to impart rotary movement to member 16 whereby gear 16d drives gear 32 thereby rotating shaft 33 in the bearings 34 and 35 and driving gear 51 which in turn drives vertical shaft 45 through gear teeth 50 thereon. Shaft 45 has a sleeve 52 secured thereon concentrically within the frame 53 of the friction disc. The shaft 45 is diametrically apertured for the passage of pin 54. The aperture 55 in shaft 45 through which pin 54 extends is elongated vertically so that the frame 53 in the friction wheel is free to move vertically within limits offered by the aperture 55. A coil spring 56 is disposed within the central socket of shaft 45 and exerts a continuous force against pin 54 and the adjusting screw head 57. By adjusting screw head 57 downwardly against coil spring 56, the vertical thrust of the frame 53 of the friction wheel is resisted so that the load which is added to the revolving doors at a predetermined rate of speed may be accurately controlled. The friction wheel 53 has a friction face 58 secured thereto adapted to be pressed into engagement with the friction

face 59 of the casing 31 for retarding the rotation of the revolving doors and holding the doors to the predetermined speed in accordance with the condition of centrifugal force which is established as the doors revolve. The sleeve 52, carried by the frame of the friction wheel 53, has clutch teeth 52a directed downwardly for normally engaging clutch teeth 60 projecting upwardly from a hub 61 on rotatable disc 62. The rotatable disc 62 has a plurality of upstanding lugs 62a thereon disposed in diametrically opposite positions on the disc 62 and serve as pivots for bell cranks 63. The bell cranks each carry weights 64 on the extremities thereof, which weights are free to move in radial planes under the action of centrifugal force. The bell cranks have pressure feet 65 on opposite extremities thereof which engage the lower face of the frame of the friction wheel 53. Under the action of centrifugal force, the weights 64 move outwardly within the hollow interior of the housing 31 and operate to force friction wheel 53 upwardly so that friction surface 58 engages beveled surface 59 in housing 31 for gradually increasing the load on shaft 45, and holding the shaft and the associated gear train and the revolving doors to the predetermined speed. The various degrees of loading on the revolving doors depend upon the amount of centrifugal force which is established. When the rate of movement is interfered with, the flywheel 62 acts as a driver, thus causing clutch 60 to raise clutch 52a. This action brings friction lining 58 in contact with friction face 59 and will stop the doors, serving as a safety device, for in case of any object or person getting caught between the doors and wall, the doors will be quickly stopped thus avoiding injury to property and people. The brake acts very quickly where a person or object stops the door and will prevent accidents which could occur if the brake did not act promptly. When the speed of the revolving door is reduced, the weight of the friction wheel 53 and the force of spring 56 acting upon pin 54 is such as to restore the bell cranks to a position immediately adjacent the upper surface of rotatable disc 62, thus returning the weights 64 to a position in which changes in speed will produce changes in angular position of the weights 64. The speed control may be adjusted for operation at selected rates of speed by adjusting screw threaded member 57 against spring 56 which bears against diametrically extending rod 54, so that the frictional load will be rendered effective at a predetermined speed. The trolley mechanism operating upon the guide rails permits the doors to be moved over to the side of opening, thereby giving a free opening so that large objects may be taken through the doors. The trolley only carries the weight of the doors. When the doors must be moved out of central position, the ejector rod 66 is given a quick vertical movement by means of the projecting lever 67 extending through slot 68 in the vertically disposed tube 2. The ejector rod 66 passes through a bushing, as indicated at 69, which is placed in the end of tube 2. Rod 66 has a diameter of approximately $\frac{1}{8}$ " and a length terminating short of the pin 18. Rod 66 always terminates beneath pin 18 allowing the installation of the equipment on doors of different heights and permitting installations to be made on old doors now in use. Upward movement of rod 66 forces pin 18 out of socket 17, enabling gear 16b to be disengaged from gear 32, so that the entire revolving door structure may be shifted on the trolley away from the speed control mechanism. 775

When it is desired to engage the speed control mechanism with the revolving door structure, the revolving doors are moved on the trolley mechanism to a position in which the pin 18 rides on beveled surface 16c of member 16 and after being depressed vertically, drops into the socket formed by sleeve 17, thereby maintaining the gears in mesh and enabling the speed control to directly function under control of the movement of the doors. In order to maintain the parts of the speed control in lubricating condition, I provide a port 71 through shaft 45 which may be closed by any suitable oil cup or device, represented generally at 70, for supplying lubricant 15 to the moving parts of the speed control.

It will be seen that under normal conditions, the rotatable disc 62, the frame 53 of the friction wheel and the rotatable shaft 45, rotate as a unit through the clutch connection formed by 20 teeth 52a and 60. Under conditions of increase in speed, however, the load, due to the vertical movement of the friction wheel of which 53 forms a part, is increased as the coupling between rotatable disc 62 and shaft 45 is decreased, 25 but the clutch teeth 60 and 52a are never disengaged. The loading of the doors will prevent racing through them. It is not intended for the speed control to exert a force great enough to cause the doors to collapse, but to add a load 30 so as to discourage the desire to race, thereby making the doors safe for everybody. The clutch is always engaged except when the door decelerates. When the door moves slower than the flywheel, the clutch partially disengages and 35 the upper jaws rise.

It will be observed that rotatable disc 62 is weighted at its periphery so that, as a flywheel, it continues to revolve by release of the kinetic energy stored therein after the driving force on 40 the doors has been released. Allowance is made in the action of the brake system to prevent sufficient movement of the revolving doors to permit injury to persons or objects caught between the ends of the door wings and the frame. The 45 character of gripping action brought about by the brake system is such, that a sufficiently rapid stopping action is obtainable to prevent injury to persons or objects. If the speed of rotation is increased beyond a safe value and the door 50 comes to rest at the limit of the peak speed, the brake will automatically allow the door to be released and to be revolved freely.

The structure of my invention has been found to be highly practical in manufacture, production and operation, and while I have described my invention in certain preferred embodiments, I desire that it be understood that modifications 55 may be made and that no limitations upon my invention are intended other than are imposed by the scope of the appended claims.

What I claim as new and desire to secure by Letters Patent of the United States is as follows:

1. In a speed control for a rotary shaft, the combination with a shaft rotatably mounted in a vertical position, a gear device driven by the said shaft, a speed control casing supported in a fixed position above said shaft, a driven gear journaled in said speed control casing and adapted to be meshed with the drive gear connected with the shaft, a plurality of control means within said speed control casing operated by said driven gear, and a friction brake within said speed control casing automatically and selectively actuated by said plurality of control means for applying a 70 retarding load to the rotary shaft.

2. A speed control for a rotary shaft comprising in combination with a frame structure, a shaft rotatably mounted beneath said frame structure, a driving gear connected with said shaft, a speed control casing mounted in fixed relation to said frame structure, a plurality of actuators rotatably mounted in said casing, a friction brake disposed in said casing and operative under control of said actuators, a driven gear meshing with said driving gear and journaled with respect to said casing for imparting rotary movement to said actuators for imparting increase in load to the rotary shaft as the speed of rotation thereof varies excessively. 10

3. A speed control for a rotary shaft comprising in combination with a frame structure, a shaft 15 mounted for rotation with respect to said frame structure, a speed control casing supported in fixed relation to said frame structure, a rotary element within said speed control casing including actuating devices and a friction brake, and 20 means interconnecting said rotatable element with the rotary shaft for loading said rotary shaft under control of said friction brake as said actuating devices are selectively effective depending upon the nature of the variation in the speed of 25 the shaft.

4. In a speed control for a rotary shaft, a frame structure, a rotary shaft mounted for rotation with respect to said frame structure, a driving gear connected with said shaft, a speed control 30 casing supported in fixed relation to said frame structure over said shaft, a central shaft journaled in said speed control casing, a driven gear journaled in said casing for establishing a driving connection between said driving gear and said 35 central shaft, a flywheel disposed concentrically around said shaft within said casing, a friction wheel in said casing slidably connected with said shaft, and means interconnecting said friction wheel and said flywheel for causing said flywheel 40 to raise said friction wheel into frictional engagement with a part of said casing when the rotary shaft is sharply decelerated, thereby instantly stopping the rotary shaft by the friction braking thus produced. 45

5. In a speed control for a rotary shaft, a frame structure, the rotary shaft rotatably mounted with respect to said frame structure, a driving gear connected with said shaft, a speed control casing supported in fixed relation to said frame 50 structure, a rotatable shaft journaled in said casing, a driven gear journaled in said casing for establishing a driving connection between said driving gear and said rotatable shaft journaled in said casing, a flywheel journaled about said rotatable shaft, a friction wheel connected with said rotatable shaft, a clutch disposed between said flywheel and said friction wheel and rotatably engaged for rotating said friction wheel and flywheel as a unit for all speeds of operation of the 60 rotary shaft below a predetermined speed, and centrifugal means carried by said flywheel for longitudinally displacing said friction wheel with respect to said rotatable shaft on conditions of excess speed of the rotary shaft for forcing said 65 friction wheel into frictional engagement with a part of said casing for applying a load to the rotary shaft. 55

6. In a speed control for a rotary shaft, a frame structure, the rotary shaft rotatably mounted 70 with respect to said frame structure, a driving gear connected with said shaft, a speed control casing supported in fixed relation to said frame structure, a rotatably driven shaft journaled in said casing, a driven gear journaled in said casing 75

for establishing a driving connection between said driving gear and said driven shaft journaled in said casing, a flywheel journaled about said driven shaft, a friction wheel connected with said driven shaft, a clutch disposed between said flywheel and said friction wheel and rotatably engaged for rotating said friction wheel and flywheel as a unit for all speeds of operation of the rotary shaft below a predetermined speed, centrifugal means carried by said flywheel for longitudinally displacing said friction wheel with respect to the driven shaft on conditions of excess speed of the rotary shaft for forcing said friction wheel into frictional engagement with a part of said casing for applying a load to the rotary shaft and spring means for adjusting the tension on said friction wheel and opposing the action of said centrifugal means.

7. A speed control for a rotary shaft comprising in combination with a frame structure, a rotary shaft rotatably mounted with respect to said frame structure, a speed control mechanism geared to rotate under control of driving forces imparted by the rotation of said rotary shaft, said speed control mechanism including a vertically disposed rotatably mounted driven shaft, a horizontally extending flywheel concentrically disposed about said driven shaft, a friction wheel secured to said driven shaft and vertically displaceable for establishing frictional engagement with a fixed part of the casing of said speed control mechanism, centrifugally actuated means connected to said flywheel and operative against said friction wheel for bringing said friction wheel into frictional engagement with the fixed casing of said speed control, and additional means actuated by the momentum of said flywheel and operative against said friction wheel for bringing said friction wheel into frictional engagement with the fixed casing of said speed control.

8. A speed control for a rotary shaft comprising in combination with a frame structure, a rotary shaft rotatably mounted with respect to said frame structure, a speed control mechanism geared to rotate under control of driving forces imparted by the rotation of said rotary shaft, said speed control mechanism including a vertically disposed rotatably mounted driven shaft, a horizontally extending flywheel concentrically disposed about said driven shaft, a friction wheel, a diametrically extending pin projecting through said friction wheel and through a longitudinally disposed diametric slot in said driven shaft, adjustable spring means extending through a bore interiorly of said driven shaft and bearing against said pin, and coacting inclined faces carried by said flywheel and said friction wheel and adapted to act under the force of momentum of said flywheel to displace said friction wheel along said driven shaft against the action of said adjustable spring for effecting frictional engagement between said friction wheel and a portion of the casing of said speed control mechanism.

9. A speed control for a rotary shaft comprising a casing, speed control mechanism disposed within said casing, a rotary shaft, means extending between said shaft and said speed control mechanism for driving said speed control mechanism in accordance with the rate of rotation of said shaft, a frusto-conical friction wheel forming part of said speed control mechanism, a frusto-conical shaped engaging surface projecting from said casing in alignment with said friction wheel and engageable by said friction wheel for establishing a braking effect upon the rotary

shaft, and means operable under conditions of excessive rates of variation of speed for producing said braking effect.

10. In a speed control for a rotary shaft, a frame structure, a rotary shaft journaled within said frame structure, a casing for speed control supported by said frame structure, a driven shaft journaled in said casing, anti-friction bearings carried by the casing of said speed control, a geared connection between said driven shaft and the rotary shaft, means in said casing operated by said driven shaft for effecting a braking action under conditions of excess speed of said driven shaft, and additional means in said casing for effecting a braking action under conditions of abnormal deceleration of said driven shaft.

11. A speed control for a rotary shaft comprising a casing, the rotary shaft journaled in a frame structure, a driven shaft journaled vertically in said casing, means for driving said driven shaft by said rotary shaft from a position exteriorly of said casing, a flywheel disposed concentrically around said driven shaft, a friction wheel slidable longitudinally with respect to said driven shaft, clutch faces normally interengaging said flywheel and said friction wheel, a plurality of bell cranks pivoted with respect to said flywheel and extending radially with respect to said flywheel, weights carried on the extremities of each of said bell cranks, the opposite ends of said bell cranks extending beneath the periphery of said friction wheel and operating to raise said friction wheel into frictional engagement with a portion of the casing of said speed control, partial disengagement of the clutch faces between said flywheel and said friction wheel being caused by deceleration of the driving shaft and also operable to produce a braking action on the driven shaft.

12. A speed control for a rotary shaft comprising a casing, centrifugal mechanism disposed within said casing, drive means exterior of said casing for imparting rotary movement to said centrifugal mechanism within said casing, a friction brake operated by said centrifugal mechanism for controlling the speed of the shaft, and auxiliary control means effective to instantaneously stop the shaft under conditions of abnormal deceleration.

13. A speed control for a rotary shaft comprising a casing, momentum mechanism disposed within said casing, drive means exterior of said casing for imparting rotary movement to said momentum mechanism within said casing, and a friction brake operated by said momentum mechanism for stopping said shaft when the speed of the shaft is decelerated at an excessive rate.

14. A speed control for a rotary shaft comprising a casing, momentum and centrifugal mechanism disposed within said casing, drive means exterior of said casing for imparting rotary movement to said momentum and centrifugal mechanisms within said casing, and a friction brake automatically selectively operative by said momentum and centrifugal mechanisms for controlling the speed of the shaft.

15. A speed control for a rotary shaft comprising in combination with a frame structure, a rotary shaft rotatably mounted with respect to said frame structure, a speed control mechanism geared to rotate under control of driving forces imparted by the rotation of said rotary shaft, said speed control mechanism including a vertically disposed rotatably mounted driven shaft, a horizontally extending flywheel concentrically

disposed about said driven shaft, a friction wheel slidably mounted on said driven shaft and rotatable therewith, coacting ratchet teeth on said flywheel and said friction wheel disposed for normally driving said flywheel through said friction wheel, said ratchet teeth adapted to act under

the force of momentum of said flywheel to displace said friction wheel along said driven shaft for effecting frictional engagement between said friction wheel and a portion of the casing of said speed control mechanism.

THURLOE M. HAGENBOOK.
